AMALGAMATION TABLE

Grant W. Berggren, 404 N. 2nd St., Hamilton, Mont.
Filed Nov. 24, 1961, Ser. No. 154,786
1 Claim. (Cl. 209—66)

This invention relates to an amalgamation table for extracting precious metals from ore.

The process of extracting precious or other metals from ore by amalgamation using the herein described apparatus comprises the steps of depositing wet ore onto a mercury coated silver plated copper plate, and imparting movement of the plate while the ore thereon is subjected to the action of a washing fluid. The metals remain on the plate while the ore is washed away. The amalgam retained on the plate is periodically removed, and the metals recovered by distilling off the mercury. Prior apparatus and those presently in use for recovering metals from ore are not able to attain the degree of efficiency which is possible with the present invention.

One of the primary objects of the invention is an amalgamation table having a novel construction which affords a high degree of efficiency in the recovery of metal from ore.

Another object of the invention is an amalgamation table having novel means for supporting the table on the frame.

Another object of the invention is an amalgamation table having novel means for imparting an orbital movement thereto.

Another object of the invention is an amalgamation table having novel means to wash the ore from which metal is to be recovered.

Another object of the invention is an amalgamation table having novel mercury trap means to recover metal which does not amalgamate.

Another object of the invention is an amalgamation table having a novel amalgamation plate assembly.

Further objects and advantages of the present invention will become readily apparent by referring to the following detailed description when taken with the accompanying drawings wherein:

FIGURE 1 is a perspective view of the amalgamation table constructed in accordance with the teachings of the present invention.

FIGURE 2 is a bottom plan view of the apparatus shown in FIG. 1.

FIGURE 3 is a top plan view of the apparatus shown in FIG. 1.

FIGURE 4 is a sectional view of the apparatus illustrating details of construction.

FIGURE 5 is an enlarged fragmentary view of the tray in which ore is deposited.

Similar reference characters refer to similar parts throughout the several views of the drawing.

Referring now to the drawings in detail, the amalgamation table of the present invention is indicated generally at 10. As shown, the apparatus comprises a frame 12 of generally rectangular configuration supported by a plurality of legs 14. The legs 14 at one end of the table 10 extend upwardly above the frame 12 and serve to support a feed hopper 16, the details and function of which will be later described.

Identical bearings indicated by numbers 18 through 25 are peripherally disposed and secured to the frame 12 as shown in FIGS. 2 and 4. Fixed to the inner corners of the frame 12 are bearing blocks 26 engaged by bearings 28 secured to the underside of tray 30 which is movably supported on bearings 18-25.

Secured to the frame 12 is a drive means 29 which imparts movement to the tray 30 on the bearings 18-25.

2

The drive means 29 is shown as an electric motor though it will be understood that any other suitable drive means can be used. Adjacent the drive means 29 there is mounted a speed reduction unit 32 which is comprised of different diameter pulleys 34, only one being shown for illustrative convenience. Spaced from the speed reduction unit 32 is a rotary crank pulley 38 mounted on frame 12. A pitman arm 40 is mounted eccentrically on the crank pulley and to the underside of the tray 30. Drive belts 42 and 44 drivingly connect the drive means 29, speed reduction unit 32, and crank pulley 38 whereby rotary motion is transmitted through the same. The rotary motion is translated into orbital motion in the tray 30 by the connecting pitman arm 40 between the crank pulley 38 and tray 30. Tension on belts 42 and 44 is regulated by crank 46, link 48, and arm 50 connected to and moving the support for pulleys 42 and 44. A spring 52 is provided to dampen end lash of the tray 30 when the same is being moved on bearings 18-25. The spring 52 is secured by one end to the frame 12 and at the other end to tray 30.

The tray 30 is provided with opposing side walls 54 and 56 and an end wall 58. The end of the tray 30 opposite the end wall 58 is open. The bottom 60 of the tray 30 and the side walls 54 and 56 and end wall 58 have adhesively secured thereto a resilient liner 62 preferably of rubber. Upon the resilient liner 62 is laid a copper plate 64 which has applied thereto on both sides a coating of silver to a thickness of at least .002". Note FIG. 5.

Removably supported in mounting grooves in the side walls 54 and 56 of the tray 30 is a frame 66 comprised of a pair of elongated side rails 68 and 70 joined by cross members 72, 73, and 74. Mounted in horizontally spaced aligned openings in the side rails 68 and 70 are a plurality of fluid carrying conduits 76. The conduits 76 are connected to each other in series by T-members 78 and pipe sections 79 and to a source of fluid (not shown) by flexible conduit 80. Valves 82 are provided whereby fluid flow to each of the conduits 76 can be regulated or shut off completely. The conduits 76 are provided with jet openings in the side walls thereof through which fluid is expelled. The conduits 76 are in overlying relation transverse the tray 30 and the silver coated copper plate 64 carried thereon and it will be apparent that the jets of fluid expelled through the openings in the walls of the conduits 76 are directed onto the plate 64 to assist in conveying the ore and non-amalgamated precious metal toward the open end of the tray 30.

Secured to the tray 30 adjacent the open end thereof is a mercury trap assembly 84. The assembly 84 is comprised of a pair of elongated transverse generally tubular members 86 and 88. Tubular member 86 is secured to a pair of plates 90 and 92 which are spaced to a relatively narrow slot 94. The tubular member 86 is provided with a slot in alignment with the slot 94 formed by the marginal edges of plates 90 and 92. Material passing through the slot 94 will drop into the interior of the tubular member 86. One end of the tubular member 86 is connected by a flexible hose 98 or the like to one of the pipe sections 79 and at its other end to a catch box 100 by conduit 102. It will be apparent that material dropping into tubular member 86 through the slot 98 will be washed into the catch box 100. Tubular member 88 has a portion thereof cut away to provide the enlarged slot or opening in the wall thereof parallel to the slot 94. The tubular member 88 is secured to the plate 92 along one side of the opening therein and has an apron 106 secured thereto along the other side of the opening. The open ends of the tubular member 88 are normally closed by plugs which can be re-

moved to allow the material which has collected therein to be removed.

There is provided, as previously stated, a feed hopper 16 secured to the upwardly extending portions of elongated legs 14. The feed hopper 16 receives ore containing precious metals from the milling or grinding unit (not shown). The feed hopper 16 has an adjustable feed gate 16' whereby the flow of ore therefrom can be regulated.

The ore is fed from the feed hopper 16 onto the silver plated copper plate 64 which has a coating of mercury thereon. The ore carrying the precious metal is washed thereon. The ore carrying the precious metal is washed by fluid expelled from the conduits 76 and is moved toward the open end of the tray 30. The washing action is enhanced by the orbital or panning movement of the tray. The precious metal in the ore is retained on the plate 64 and periodically scraped therefrom. The scraping of the amalgam from the plate 64 is easily accomplished by removing the frame 66 which carries the conduits 76.

The orbital or panning action of the tray 30 tumbles the wet ore and the water from the conduit 76 in many directions thereby preventing the ore from bedding. Since the precious metal is heavier than the ore itself it sinks to the bottom coming in contact with the live mercury spread on the silver plated copper plate 64 causing the same to amalgamate and stay thereon until scraped off at a later time.

Since the slot 94 in the first tubular member 86 is relatively narrow it will catch and thereby save live mercury without allowing any of the ore to be washed into the catch box 100. When too much mercury is applied to the silvered plate 64 it will be lost in the liquid moving over the tray 30. Also, cold water may flour some of the mercury which would also be lost if no means are provided to save it. The slot in the second tubular member 86 being somewhat wider will catch any rusty precious metals that will not amalgamate.

Precious metal which has not been retained on plate

64 is caught in the trap assembly 84 as the ore is washed toward the open end of the tray 30. The first tubular member 86 catching the amalgam which has not remained on plate 64 and the second tubular member 88 catches the precious metal which will not amalgamate.

While the invention has been described in its preferred embodiment, variations and modifications will become apparent to those skilled in the art, such modifications and variations are considered to be within the purview of the appended claim.

I claim:

An amalgamation table for extracting precious metals from an ore comprising a frame, bearings secured to said frame, and an amalgamation tray movably supported on said bearings, said tray having a bottom, side walls, an end wall at one end and being open at its other end, conduit means mounted in superimposed relation to said tray, said conduit means having wall portions defining openings therein to direct jets of fluid onto said tray, ore feeding means positioned over said one end of said tray, drive means operatively secured to said tray to move the same on said bearings in an orbital path, and a trap assembly positioned adjacent said open end of said tray, said trap assembly including a first tubular member having means defining a narrow slot extending transversely of said tray, means operatively connected to said conduit means to drain said first tubular member, and a second tubular member having means defining a relatively wider slot extending transversely of said tray.
